UNITED STATES PATENT OFFICE.

EVERETT L. TOWNSEND, OF LA CROSSE, WISCONSIN.

AUXILIARY WORK-REST.

1,274,215.

Specification of Letters Patent. Patented July 30, 1918.

Application filed February 2, 1918. Serial No. 215,144.

To all whom it may concern:

Be it known that I, EVERETT L. TOWNSEND, a citizen of the United States, residing at La Crosse, in the county of La Crosse and 5 State of Wisconsin, have invented certain new and useful Improvements in Auxiliary Work-Rests, of which the following is a specification.

My invention relates to an improved work 10 rest and is adapted for association with a carpenter's miter box to support work, especially long work in such a manner that it will not tilt but will have a firm bearing.

I aim to provide an article of this kind 15 which is easily and quickly manufactured and to particularly provide one having a rod or the like performing the two functions of anchoring the article to a work-bench and of a means whereby the article may be ad- 20 justed to vary its height relative to the miter box or equivalent device.

Additional advantages and objects will appear as the description progresses herein- 25 after in connection with accompanying drawings illustrating one preferred embodiment and wherein:—

Figure 1 is a top elevation of the carpenter's work-bench, with a miter box thereon, work associated therewith and my im- 30 proved rest in operative relation therewith;

Fig. 2 is a vertical sectional view of my improved rest;

Fig. 3 is a cross sectional view on the line 3—3 of Fig. 2, and

Fig. 4 is a plan view of the table member 35 of the rest.

Referring specifically to the drawings, a work-bench is shown at A and a miter box is shown at B, in order to exemplify my im- 40 provedments. Work is shown at C, as resting on the improvement designated generally D.

My improved rest comprises a base mem- 45 ber 5 which rests directly on the top of the table or work-bench which is designated 6.

On the top of the base 5, a bearing 7 is prefer- 50 ably formed, through which a rod 8 slides vertically. The table top is provided with any desired number of vertical openings 9 into which the rod 8 selectively extends in order to anchor my improved device. If the rest is to be permanently secured to the table

top, any desired number of openings or ap- 55 tures 10 may be provided in a base flange 11 of the base 5, through which screws or other fastening means may be driven into the table top 6. The uppermost member of 60 the device is a table 12 which has a flat top as shown and which is provided with a central hub at 13 from which ribs 14 extend outwardly. Rod 8 extends into the hub 13 and in any desired manner is rigidly 65 connected thereto so that in the event the rod 8 is adjusted vertically, the table 12 will move therewith. By reason of the connection of table 12 with the rod 8, said table is 70 adjustable vertically relatively to the base 5. In order to secure the rod and table in ad- justed positions, a set-screw or the equivalent as suggested at 15 may be employed, which is mounted in an enlarged portion 16 of the base and which may be turned to bind 75 against the rod 8 frictionally.

If the device is used in the relation shown 80 in Fig. 1, it will be realized that it acts as an auxiliary for the bed plate of the miter box in order to firmly support the work, es- 85 pecially when the work is long. The article may be removably or permanently fastened to the bench top 6 at the option of the operator and according to the nature and size of the work, placed in any position relative to the miter box desired. The rod 8 serves the double function of anchoring the device and also as a means which may be fastened to se- 90 cure the table 12 at various heights.

When securing the device to the top 6, the rod 8 is inserted into the desired opening 9. The article is then adjusted relatively to the work and to the level of the bed plate of the miter box by loosening the set screw 15 and 95 raising the table or rod 8, after which the set screw 15 is tightened into binding relation with the rod 8, to maintain the table in the proper adjusted position.

Since I have described merely one pre- 95 ferred embodiment of the invention, it is to be understood that changes in the details of construction may be resorted to provided they fall within the spirit and scope of the invention as defined by appended claim. 100

I claim:—

An auxiliary work rest having a table

member, a conical shaped base member, a rod extending from the table member through the base member, said rod being slideable through and extending below said base member whereby it may function as an anchor, means to secure said rod against sliding movement in the base member, and said base member having a flange provided with

a plurality of openings so that the same may be held against movement.

In testimony whereof I affix my signature in presence of two witnesses.

EVERETT L. TOWNSEND.
